UNITED STATES PATENT OFFICE.

FRANK A. WILMOT, OF BRIDGEPORT, CONNECTICUT.

DESIGN FOR A SHEET-METAL TUBE-BLANK.

SPECIFICATION forming part of **Design No. 27,543**, dated **August 17, 1897**.

Application filed May 11, 1897. Serial No. 636,110. Term of patent 14 years.

To all whom it may concern:

Be it known that I, FRANK A. WILMOT, a citizen of the United States, residing at Bridgeport, in the county of Fairfield and State of Connecticut, have invented and produced a new and original Design for Sheet-Metal Tube-Blanks; and I do hereby declare the following to be a full, clear, and exact description of the same, reference being had to the accompanying drawing, forming a part thereof, in which the figure represents a plan view of a blank or strip of sheet metal the edges of which are shaped according to my design, the ends of the blank being broken away to reduce the size of the figure.

The leading feature of my design consists in the sheet-metal blank having irregular edges composed of rounded projections and angular projections, there being two angular projections separated by a rounded recess

between each two of the rounded projections.

In the drawing the rounded projections are represented at 1, and between each two thereof are two angular projections *a a*, which are separated from each other by a rounded recess 2 of a width less than the width of the projections 1. Between the rounded projections 1 and the angular projections *a* are angular recesses *b*.

Having described my invention, what I claim is—

The design for sheet-metal tube-blanks substantially as herein shown and described.

In testimony whereof I affix my signature in presence of two witnesses.

FRANK A. WILMOT.
